UNITED STATES PATENT OFFICE

99,343

DESIGN FOR AN ILLUMINATOR FOR X-RAY FILMS OR SIMILAR ARTICLES

Russell S. Cheney, Evanston, Ill.

Application February 29, 1936, Serial No. 61,426

Term of patent 7 years

To all whom it may concern:

Be it known that I, Russell S. Cheney, a citizen of the United States, residing at Evanston, in the county of Cook and State of Illinois, have invented a new, original, and ornamental Design for an Illuminator for X-Ray Films or Similar Articles (Case 1), of which the following is a specification, reference being had to the accompanying drawing, forming part thereof.

Fig. 1 is a view in perspective of the front and one end of the illuminator; and

Fig. 2 is a view in perspective of one end and the rear portions of the illuminator.

I claim:

The ornamental design for an illuminator for X-ray films or similar articles, as shown.

In witness whereof, I hereunto subscribe my name, this 27th day of February, 1936.

RUSSELL S. CHENEY.
